PROCESS OF TREATING HYDROCARBON OILS

Wallace A. Craig, Los Angeles, Calif., assignor
to Vapor Treating Processes, Inc., Los Angeles,
Calif., a corporation of California

Application June 30, 1936, Serial No. 88,100

4 Claims. (Cl. 196--36)

This invention pertains to an improved system or method of treating, purifying and refining hydrocarbon oils with maintained aqueous solutions of metallic salts. More specifically, this invention pertains to improving the treating characteristics of metallic salt solutions in order to maintain definite concentrations thereof at the best or more desired treating temperatures, when used to purify and refine mineral hydrocarbon oils in vapor phase, such as gasoline or naphtha, or other petroleum oil products derived by distillation or cracking of mineral oils.

Treatment of hydrocarbon oils in vapor phase with maintained aqueous solutions of metallic salts is generally known in the refining art, in which the degree of refinement by the treatment is determined, in part, by the concentration of the metallic salt maintained in the liquid phase, and the desired concentration of the treating solution has been generally controlled primarily by controlling the temperature of the system and the partial pressure of the water in the vapor phase.

My invention is an improvement in the method described in U. S. Patent #1,790,622, granted to Arthur Lachman, dated January 27, 1931, for Method of refining mineral oils, and U. S. Patent #1,809,170, granted to Arthur Lachman, dated June 9, 1931, for Process of refining hydrocarbons, which disclose methods of refining hydrocarbon oils in vapor phase with water solutions of the metallic salts of zinc, copper, cadmium, mercury, iron, chromium, manganese, aluminum, nickel or cobalt, which may be the chloride, bromide, sulphate, nitrate, and also any of the water soluble salts of the above named metals of organic acids, such as the sulphonc acid of benzol, toluol, xylol, or the sulpho acids derived from the treatment of petroleum oils with sulphuric acid.

The method described in the aforesaid patents for refining oil comprises, passing the oil, such as gasoline stock, in vapor phase through and in contact with a hot water solution of any of the aforesaid metallic salts, in which a tower filled 45 with contact material and a substantially concentrated water solution of the metallic salt is employed.

While it is possible to maintain any desired concentration of the metallic salt in the liquid phase by the proper choice of temperature and partial pressure of water vapor, the operating conditions during the treatment of a light petroleum distillate, such as naphtha stocks, are restricted by the characteristics of the latter. In 55 order to maintain the distillate or naphtha stock

in vapor phase during treatment, certain conditions of temperature and vapor pressure must be observed. It is necessary, therefore, to choose operating conditions that will maintain the concentration of the salt solution at the desired 5 strength and at the same time maintain the distillate or naphtha stock under treatment in vapor phase.

The treatment of hydrocarbon mixtures containing unsaturated hydrocarbons with metallic 10 salt solutions causes some of the latter to polymerize or condense to form materials of higher molecular weight. The characteristics of the polymers and condensed materials depends upon the characteristics of the original unsaturates and 15 the severity of treatment, and it has been observed that some of the reaction products are recovered in the gasoline fraction, while others are removed in the higher boiling portions of the discharged material. Fractionation will effect the 20 removal of high-boiling polymers and allow the recovery of a treated distillate having favorable characteristics, such as good color, good color 25 stability when exposed to sunlight, absence of gums and gum forming constituents, etc.

There are times when it is beneficial to maintain the salt solution at a relatively low concentration. If it becomes desirable to lower the concentration within the treating vessel, it may be accomplished by lowering the temperature or increasing the partial pressure of the water in the 30 vapor phase, or both. However, such changes also affect the liquid-vapor equilibrium of the hydrocarbon oil, as shown in the following Table 35 No. 1, which illustrates some of the varying treatment conditions which may be employed in purifying a cracked gasoline stock.

TABLE NO. 1

	Column				40
	1	2	3	4	
Metallic salt used for treating	ZnCl ₂	ZnCl ₂	ZnCl ₂	ZnCl ₂	45
Treating temperature, °F	350	335	350	335	
Treating pressure, lb./sq. in. gage	18	18	18	18	
Mol. per cent of water in vapor phase	40	40	55	55	
Zinc chloride concentration, wt. percent	82.5	79	80	77.5	50
Average boiling point at 1 atmos. pressure of hydrocarbons in vapor phase, °F	330	315	345	330	

Under the chosen conditions, as shown in column 1 of Table No. 1, a zinc chloride concentration of 82.5% is obtained, and the hydrocarbon 55

oil in vapor phase has an average boiling point of approximately 330° F. If the conditions of pressure and water vapor pressure are maintained but the temperature is lowered to 335° F., as shown in column 2, the zinc chloride concentration will be reduced, and at the same time the average boiling point of the hydrocarbons will be reduced, and a portion of the hydrocarbons which were formerly in vapor phase will condense within the 10 treater.

Column 3 shows the effect of changing the proportion of water vapor within the treater and maintaining the temperature and pressure constant. Such a change will reduce the zinc chloride concentration of the treating solution and increase the average boiling point of the hydrocarbons in vapor phase, provided, of course, that there are hydrocarbons present in liquid phase to allow this increase to take place.

20 Column 4 shows the conditions necessary to reduce the zinc chloride concentration, and at the same time maintain the average boiling point of the hydrocarbons in vapor phase at approximately the same value as that shown in column 25 1. It is, therefore, evident that conditions of temperature, pressure and water vapor pressure can be chosen so that the concentration of zinc chloride in solution and the average boiling point of the hydrocarbons in vapor phase can be controlled to a limited extent. The same sort of control can be achieved if other treating reagents are used when the characteristics of the treating solution are known. It is seen that:—

- 35 1. Temperature reduction decreases the concentration of the metallic salt solution;
2. Temperature reduction decreases the average boiling point of the hydrocarbons in the vapor phase;
3. Increase in water vapor pressure decreases the concentration of the metallic salt solution;
40 4. Increase in water vapor pressure increases the average boiling point of the hydrocarbons in the vapor phase.

45 From an economical point of view, it is desirable to reduce the steam requirements of the treating system to a minimum. It is shown in the above discussion, however, that higher temperatures would be required to offset the effect of reduced water vapor pressure upon the average 50 boiling point of the hydrocarbons in the vapor phase. These conditions would affect the treating solution, causing it to become more concentrated. Inasmuch as the severity of treatment depends in part upon the concentration of the 55 metal salt, it is evident that high temperature and minimum steam addition will give more

severe treatment than will occur with lower temperature and greater additions of steam. Some hydrocarbons are adversely affected by severe treatment, and it is necessary to subject stocks of this nature to the milder action of more dilute reagents. One is, therefore, required to sacrifice economy in steam consumption in order to avoid over-treatment of such materials.

Now I have discovered that, in the refining of vaporized hydrocarbons such as naphtha or gasoline stocks with aqueous zinc chloride and other like metal salt treating solutions, the aforesaid difficulties may be overcome by dissolving in the treating solution certain compounds which will decrease the vapor pressure of the treating solution at a given temperature, or modify the temperature-vapor pressure-concentration relationship. Such compounds, used by my invention to modify the temperature-vapor pressure-concentration relationship, may be inert or non-reactive salts which are soluble in the treating solution, such as calcium chloride, sodium chloride, potassium chloride, and the like, dissolved in treating solutions of zinc chloride, copper chloride, aluminum chloride, and the like, as described in my pending application Serial No. 60,039, filed January 21, 1936, for Process of treating hydrocarbon oils.

In treating solutions made from metal sulphate salts, such as zinc sulphate, copper sulphate, etc., non-reactive salts would be employed to modify the temperature-vapor pressure-concentration relationship, such as sodium sulphate, potassium sulphate, and the like, to avoid reactions which would cause precipitation, or removal of any of the components of the treating solution. 30 35

I have further discovered that soluble organic salts of the pyridine type will also modify the temperature-vapor pressure-concentration relationship of treating solutions. These compounds may be pyridine, pyridine homologues, or the nitrogen base compounds extracted from petroleum oils, which may be added to the treating solution in the form of bases and allowed to react with the acid which is formed by hydrolysis of the metal salt treating agent, or these nitrogen bases may be converted into salts by the addition of acid, such, for example, as by the addition of hydrochloric acid to produce hydrochlorides, and then added in this form to the metal salt treating solution.

The following Table No. 2 illustrates the changes in the boiling points produced by the addition of petroleum base hydrochlorides to zinc chloride treating solution, and the saving in steam effected thereby in refining gasoline stocks. 55

TABLE NO. 2
*Comparison of treating characteristics of zinc chloride solution and zinc chloride solution containing
 petroleum base hydrochlorides having a ratio of base to zinc chloride of 0.090*

Table No. 2 shows that at constant conditions of temperature, pressure and partial pressure of water vapor, the zinc chloride concentration is lowered by the addition of petroleum base hydrochlorides. At constant zinc chloride concentration, the presence of bases allows operation at lower pressures, or lower partial pressure of water vapor. At constant zinc chloride concentration, constant pressure and constant partial pressure of water vapor, higher temperatures can be employed.

An object of the invention is to refine hydrocarbons in vapor phase at a given temperature, with a water solution of a metallic salt, at a desired vapor pressure.

Another object of the invention is to refine hydrocarbons in vapor phase at a given temperature, with a water solution of a metallic salt treating agent, maintained at a desired vapor pressure by the addition of an inert compound which is soluble in the treating solution.

Another object of the invention is to refine hydrocarbon oil vapor by contact with a reactive salt solution containing a relatively non-reactive salt or compound dissolved therein, in quantities sufficient to modify the temperature-vapor pressure-concentration relationship of the solution to the desired degree.

Various other objects and advantages of the present invention will be apparent from the description of the preferred form or example of the method embodying the invention. For this purpose reference is made to the accompanying drawings.

Figure I shows the relationship at atmospheric pressure of boiling point and concentration of aqueous zinc chloride solutions in which varying amounts of nitrogen base hydrochlorides are dissolved. The ratios shown in the legend on the figure are calculated from the content of free bases rather than the content of base hydrochloride. Each curve represents a constant ratio of nitrogen bases to zinc chloride. Similar curves can be prepared to show the same relationship at pressures other than atmospheric, or for other treating solutions.

Figure II represents generally apparatus in which the invention may be performed, in which 50 I represents a treater for contacting hydrocarbon oil vapor with refining agent. The lower section of treater I is filled with bubble cap trays 2, and provided with a compartment trap 3 stationed above the last tray or row of bubble caps. Pipe 4, controlled by valve 5, connects treater I 55 near the bottom to a source of hydrocarbon vapor to be treated, such as a fractionating column, still, or other form of vaporizer. Pipe 6, controlled by valve 7, connects hydrocarbon vapor pipe 4 to a source of the treating solution. Pipe 60 8, controlled by valve 9, connects pipe 4 to a source of steam. Pipe 10, controlled by valve 11, connects treater I at the bottom to a storage for waste supply, not shown. Pipe 12, controlled by valve 13, connects the compartment trap section 65 of treater I to a source of steam. A discharge pipe 14, controlled by valve 15, connects the compartment trap section of treater I to a storage for spent treating solution, not shown. Pipe 16 70 connects treater I at the top to allow the vapors to pass to other equipment for further processing, known in the art.

The preferred operation as carried out in the apparatus just described, is as follows:

The treating solution is preferably a water solution of zinc chloride and petroleum base hydro-

chlorides, in which the ratio of petroleum bases to zinc chloride ranges from about 0.09 to 0.65 part by weight of petroleum bases to 1 part by weight of zinc chloride. While the preferred salts employed to make the treating solution are 5 zinc chloride and petroleum base hydrochlorides, it is to be understood that any of the other salts or mixtures thereof and compounds heretofore enumerated may be used in like manner at various ratios and concentrations to suit the oil to be 10 treated and the product desired. However, in order to simplify this example, the conditions which are presented in columns 1 and 2 of Table No. 2 will be used to illustrate my improved method of operation.

Treater I is first filled up to the level of the discharge pipe 14 with the treating solution to be employed, heated to a desired temperature, preferably ranging from about 360 to 390° F., by a heater not shown, which discharges the heated 20 solution through pipe 6, controlled by valve 7, pipe 4, and into said treater I near the bottom.

Hydrocarbon oil vapor, such as gasoline or naphtha stock, coming from any of the known refinery vaporizers, or vaporizer and fractionating system, at or above the vapor temperature of the stock to be treated, passes through pipe 4, controlled by valve 5, and into the lower section of treater I. At the same time a regulated quantity of steam, which may be superheated to any 30 required temperature so as to maintain the oil vapor at any required treating temperature, is continuously passed into the oil vapor passing through pipe 4, the steam coming through pipe 8, controlled by valve 9. The treating solution may 35 also be continuously or intermittently introduced into pipe 4 through pipe 6, controlled by valve 7, in quantities sufficient to maintain the treating solution in treater I at the required strength and purity to continuously effect uniform treatment of 40 the oil vapors.

The hydrocarbon vapors, commingled with steam, pass from pipe 4 into treater I, and are 45 therein intimately contacted with treating solution and treated to the required degree as they pass up through the bubble cap tray system 2. The contents of the treater are kept at a temperature of 335° F., a pressure of 40 pounds per square inch absolute, and an absolute water vapor pressure of 14.7 pounds per square inch. 50 Under these conditions, the aqueous treating solution will contain approximately 74.6% by weight of zinc chloride, and petroleum base hydrochloride, calculated as free bases, amounting to about 6.7%. The hydrocarbons in vapor phase 55 will be found to have an average boiling point of approximately 295° F. It might be pointed out at this time that, under identical conditions within the treater except that the petroleum bases be absent, the concentration of zinc chloride in the solution would be approximately 80%, as shown in column 1 of Table No. 2.

The spent or partially spent treating solution is continuously or intermittently discharged 65 from treater I through pipe 14, controlled by valve 15, to a storage tank not shown, and may be thereafter recovered for reuse by known methods. Steam may also be introduced into the upper section of treater I through pipe 12, controlled by valve 13, to maintain the oil in vapor phase. 70 From treater I, the treated oil vapors and gaseous products of reaction pass through pipe 16 to other equipment known in the art, in which the purified hydrocarbons are separated from undesirable products of reaction.

5 The novel feature of my invention is the use of petroleum base hydrochlorides, or other inert compounds, to alter the concentration of the active metallic salt in the treating solution, so that greater flexibility of operation may be obtained. By their use, lower concentrations can be obtained under constant operating conditions, or 10 higher temperature can be employed without increasing the concentration, and thereby reduce the consumption of steam.

10 While the process herein described is well adapted for carrying out the objects of the present invention, it is to be understood that various modifications and changes may be made without departing from the spirit of the invention, such, 15 for example, as the use of other forms of contact towers or mechanical mixers, and the invention includes all such modifications and changes as appear within the scope of the appended claims. It also includes the treatment of 20 normally gaseous unsaturated hydrocarbons, by which they can be converted to hydrocarbons of greater molecular weight. By means of my invention it is possible to increase the treating 25 temperature to a marked extent, and still maintain the active treating material as a mobile aqueous solution, and at the same time maintain a relatively low pressure upon the treating vessel.

I claim:

30 1. A method of refining hydrocarbon oil vapor which comprises, contacting the oil vapor mixed with steam at refining temperatures with aqueous, reactive, maintained salt solution of a "heavy metal" containing petroleum base salts dis-

solved therein, in sufficient amount at the temperature and pressure employed in the refining process to modify the temperature-vapor pressure-concentration relationship of the solution sufficiently to refine the oil vapor at required temperature and pressure. 5

2. In the process of refining hydrocarbon oil vapor mixed with steam by contact with aqueous, reactive, maintained salt solution of a "heavy metal" at refining temperature, the improvement which comprises, modifying the temperature-vapor pressure-concentration relationship of said salt solution sufficiently to refine the oil vapor at required temperature and pressure, by dissolving therein organic nitrogen base hydrochloride salts derived from petroleum oils. 10 15

3. In the process of refining hydrocarbon oil vapor mixed with steam, by contact with a water solution of zinc chloride at refining temperatures, maintained at constant concentration, constant pressure and constant water vapor pressure, the improvement of maintaining a higher treating temperature by adding to the zinc chloride solution salts of petroleum bases, in amounts sufficient to refine the oil vapor at a required treating temperature. 20 25

4. In the process of refining hydrocarbon oil vapor mixed with steam, by contact with a water solution of zinc chloride at refining temperatures, maintained at constant concentration, constant pressure and constant water vapor pressure, the improvement as in claim 3 in which the petroleum base salts are hydrochlorides. 30

WALLACE A. CRAIG.
